UNITED STATES PATENT OFFICE.

STEPHEN S. HOE, OF TARRYTOWN, NEW YORK.

ELECTROTYPE-PLATE.

SPECIFICATION forming part of Letters Patent No. 286,821, dated October 16, 1883.

Application filed May 16, 1883. (No model.)

To all whom it may concern:

Be it known that I, STEPHEN S. HOE, a citizen of the United States, residing in the city of Tarrytown, county of Westchester, and State of New York, have invented certain new and useful Improvements in Electrotype-Plates, fully described and represented in the following specification and the accompanying drawings, forming a part of the same.

- 10 It is well known to those familiar with the art of printing from electrotype-plates that before such plates can be used it is necessary to provide them with a backing of type or other similar metal; and also that, owing to the frail 15 nature of these plates and their consequent liability to become cracked or distorted if bent after the backing is applied, it is necessary in preparing these plates for use upon a rotary printing mechanism to bend them to fit the 20 curvature of the printing-cylinder before the backing is applied. In practice, however, it has been found very difficult to accomplish this bending in so accurate a manner as to produce a plate of regular and uniform curvature. 25 It is also well known to those familiar with the art of electrotyping that the weakest parts of these plates are upon the lines of the column-rules, and that in handling or bending these plates prior to the application of the 30 backing they are very liable to become broken on these lines, and thereby damaged or entirely destroyed.

It is the object of the present invention to obviate these difficulties; and to these ends 35 the invention consists in the method of backing electrotype-plates, which will be herein-after fully explained and particularly pointed out.

In the accompanying drawings, Figure 1 is 40 a plan view of the back of an electrotype-plate for one page of a three-column paper or magazine. Fig. 2 is a cross-section of the same upon an enlarged scale taken between two lines of words. Figs. 3, 4, and 5 are like views, illustrating the several operations involved in fitting the plate for use upon a printing-cylinder; and Fig. 6 illustrates a modification to be referred to.

Referring to said figures, it is to be understood that *a* represents an ordinary electro-

type-plate in the condition in which it comes from the matrix, the back being exposed in Fig. 1. The plate at this stage is a very thin piece of copper, exceedingly limber, and, where bent at an abrupt angle for any considerable distance, as at the column-rules *c*, very weak and liable to be broken, if subjected to any considerable strain, as in handling or bending. If the plate, when in this condition, is provided with a backing of the ordinary thickness, and then bent so as to fit the curvature of the printing-cylinder, it will be very liable to be ruptured or distorted so as to be worthless, which fact, as before stated, makes it necessary to give to the plate the proper curvature before the backing is applied. On the other hand, it is very difficult to bend the plate to the proper shape at this stage—first, because of its liability to break upon the column-rules, and, second, because its exceeding thinness and the irregularity of its surface render it almost impossible to make it assume an even curvature. The first of these difficulties is overcome in the present invention by filling or partially filling the channels at the back of the column-rules with lines *d* (see Fig. 3) of tin, solder, or type-metal, which so strengthens the plate that it can be handled without danger of cracking or breaking. These lines will also give such a degree of rigidity to the plate that in many cases it can be successfully bent to the proper curvature to receive the proper backing. In most cases, however, it will be found preferable, while the plate is still in its flat condition, to not only fill the said channels, but to also cover its entire back with a thin coating, *e*, (see Fig. 4,) of tin or type-metal. The lines *d* and coating *e* may in such case be applied together, as indicated in Fig. 6, or separately, as indicated in Fig. 4. 90 This coating will give to the plate a sufficient degree of rigidity, so that it can be bent to and will retain a uniform and even curvature while the main backing is being applied, and yet will not, owing to its thinness, cause the plate 95 to break or become distorted in the process of bending. After the thin coating *e* has been applied the plate will be bent to the proper curvature in the usual manner, and will then receive the usual backing, *g*, as shown in Fig. 100

5, after which it will be ready to be placed upon the printing-cylinder.

What I claim is—

- 5 1. That improvement in the art of backing electrotype-plates which consists in providing the channels at the back of the column-rules with lines of tin or similar metal previous to the application of the backing, all substantially as described.
- 10 2. That improvement in the art of backing electrotype-plates which consists in filling the channels at the back of the column-rules, and

covering the entire back of the plate with a thin coating of tin or similar metal previous to the application of the backing, all substantially as described. 15

In testimony whereof I have hereunto set my hand in the presence of two subscribing witnesses.

STEPHEN S. HOE.
